UNITED STATES PATENT OFFICE.

JOHN H. PATTERSON AND JOHN F. HEADY, OF DAYTON, OHIO, ASSIGNORS
TO THE NATIONAL CASH REGISTER COMPANY, OF SAME PLACE.

CASH REGISTER AND INDICATOR.

SPECIFICATION forming part of Letters Patent No. 380,513, dated April 3, 1883.

Application filed December 2, 1887. Serial No. 256,743. (No model.)

To all whom it may concern:

Be it known that we, JOHN H. PATTERSON and JOHN F. HEADY, both citizens of the United States, residing at Dayton, in the county of Montgomery and State of Ohio, have invented certain new and useful Improvements in Cash Registers and Indicators, of which the following is a full, clear, and exact description, reference being had to the accompanying drawings, forming part of this specification.

Our invention has for its object an improvement in the construction of this class of machines, and its novelty will be herein set forth, and specifically pointed out in the claims.

15 In the accompanying drawings, Figure 1, Sheet 1, is a front elevation of a register and indicator embodying our invention. Fig. 2, Sheet 2, is a sectional side elevation taken through the dotted line $x\bar{x}$ of Fig. 1. Fig. 3,

20 Sheet 3, is a front elevation of the registering mechanism removed from the case. Fig. 4, Sheet 3, is a sectional front elevation of the registering mechanism through the dotted line $y\bar{y}$ of Fig. 5. Fig. 5, Sheet 4, is a plan view 25 of the registering mechanism. Fig. 6, Sheet 4, is an enlarged section through the axes of the registering-shaft and sleeve with connected parts. Fig. 7, Sheet 4, is a sectional front elevation through the dotted line $z\bar{z}$ of Fig. 6.

30 The same letters of reference are used to indicate identical parts in all the figures.

We provide any suitable case, A, having in front a dial, B, and in its lower part a drawer-compartment for the money-till C. The dial has upon its face two sets of numbers—an outer 35 one, beginning with 0 at the top and extending to the right around the dial in multiples of five up to 95, and representing cents, and an inner one, extending from the top to the 40 left, representing dollars—in this instance \$1, \$2, \$3, \$4, and \$5—as shown in Fig. 1.

In a suitable frame-work within the case, just behind the dial—in this instance consisting of two upright plates, D, some distance 45 from each other and parallel to the dial—is the registering mechanism.

Journalled in the rear plate D, Figs. 5 and 6, is a shaft, E, which extends forward through a sleeve, F, journalled in the front plate D, 50 said shaft projecting through the front of the sleeve and both said shaft and sleeve project-

ing through an opening in the front of the dial. Secured to or integral with the shaft E, near the rear plate D, is a double ratchet, $a\bar{b}$, the outer part, a , of which is of greater diameter 55 than the inner part, b , and between said double ratchet and the rear plate D is a pinion, G, loose upon the shaft E and of a diameter equal to or greater than the ratchet a . The inner end of the sleeve F abuts against the ratchet 60 a , and said sleeve has secured to or integral with it a ratchet, H, just in front of the front plate D.

Loose upon the sleeve F, just in front of the ratchet H, is a second combined ratchet and 65 registering wheel, I, of a less diameter than the ratchet H. The face of the wheel I is numbered to correspond with the outer numbers upon the dial B, as seen in Fig. 3, though said numbers are arranged in an opposite direction 70 to those on the dial. The face of this wheel I is close to and just behind the dial B. The pinion G and ratchet b , as seen in Fig. 7, are connected by a spring-dog, c, which, pivoted to the side of the pinion, engages with the 75 ratchet. The ratchet H and wheel I are similarly connected, as seen in Fig. 3, by a spring-dog, d, pivoted to the side of the ratchet H and engaging with the teeth of the wheel I. The shaft E and sleeve F are connected by a 80 coiled spring, J, whose inner end is secured to the sleeve F and whose outer end is secured to a stud, e, projecting from the side of the ratchet a , as seen in Figs. 5 and 6.

An operating index-hand, K, is secured in 85 front of the dial B to the sleeve F and extends to the outer row of numbers, while a shorter operating index-hand, L, is secured to the shaft E and extends out to the inner row of numbers, as seen in Fig. 1. The spring J is partially wound up and its tension is supported on the one side by a stop, f, on the dial B, against which the hand K is arrested from movement to the left, and on the other side by a pin, g, projecting from the ratchet a , and which 90 comes in contact with one of the tie-rods M uniting the plates D when the hand L points to "0," and which prevents the rotation of the hand to the right. Each of the hands K L is provided with a projecting operating pin or handle, h. It results from this construction 95 that upon turning the hand K to the right the

spring J is wound up from the inside, while upon turning the hand L to the left the spring is wound up from the outside.

Instead of having two stops—one, f, for the hand K and one, g, for the ratchet a and hand L—the single stop f might be interposed between the hands K and L on the face of the dial, to act as a stop for both of them, the hand K bearing against its right side and the hand L against its left side, or any other suitable stop or stops may be used for the hands.

Journalized in the plates D are six shafts, N' N'' and O' O'', in two banks of three each, the O's being arranged directly over the N's of similar powers. Each of these shafts has upon its forward end a registering-disk just behind the dial B and in line with the wheel I, and is provided on its face with numbers in multiples of one from 0 to 9. Just behind the disk P' of the shaft N' and upon said shaft is a pinion, i, with ten teeth, with one of which teeth a pin, j, projecting from the wheel I, engages at every complete revolution of said wheel I to turn the disk P' one-tenth of a revolution. A second pinion, k, upon the shaft N'' is provided with a projecting pin or lug, l, which at each complete revolution of the disk P' engages with a tooth of a similar pinion, m, upon the shaft N'' to turn the disk P'' one number. This pinion is likewise provided with a pin or stud, n, which at each complete revolution of the disk P'' engages with a pinion, o, upon the shaft N''' to turn the disk P''' one number. The shafts O', O'', and O''' are likewise provided with pinions p q r, respectively, the first having its pin s and the second its pin t, as in the lower bank, and for the same purpose. The pinion p meshes constantly with the pinion G upon the shaft E, as seen in Fig. 4, and suitable springs or brake-dogs, u, are employed for all of the pinions of the registering disks. It will thus be seen that there are two banks of registering wheels or disks, the upper one of which is operated by the hand L and shaft E through the medium of the ratchet b, dog e, and pinion G, while the lower one is operated by the hand K and sleeve F through the medium of the ratchet H, dog d, and wheel I, as will be readily understood.

There are a series of reading-openings, v, through the dial B, as seen in Fig. 1, one for each of the registering disks and the wheel I, and so arranged as to expose but one number on each disk at a time. A slide, R, (shown in dotted lines in Fig. 1,) is arranged to be slipped through the side of the case behind the dial to cover all of the registering-disks and to be locked, except when the proprietor wishes to read off the amounts registered, at which time it may be unlocked and removed.

S, Fig. 4, is a spring locking-dog engaging with the ratchet a, and T is a similar dog engaging with the ratchet H.

Upon the same pivot, w, which secures the dog T to the front plate D is a spring tripping-arm, U, to whose outer end is pivoted a tripping-dog, a', engaging with the beveled

end of the pivoted bell-crank V, to the upper end of which is secured a gong-hammer, W, which, upon the operation of the lever U, is caused by the retraction of a spring, b', engaging with the bell-crank, to strike a gong, X, secured to the plate D, as shown.

If desired, the dog T and tripping arm U may be made integral.

Y is a spring locking-dog for the wheel I, pivoted, as at c', to a stud projecting from the plate D.

A', Fig. 2, is a releasing-key pivoted between lugs d' within the case, and having its forward end projecting through an opening in the case and provided with an operating-button. Its rear end has pivoted to it the usual or any suitable drawer-bolt, C', for holding the drawer C locked, except when the key A' is depressed, whereupon the drawer is unlocked and is partially projected from its compartment by the usual spring, D'.

E' is the usual resetting spring for the key A'. A link, F', pivoted to the key A', extends up within the case between the dogs S and T, to which and to the tripping-arm U it is connected by the cross-bar e', whose ends are secured in apertures or slots in the dog S and the arm U, and which engages with the recessed side of the dog T, as seen in dotted lines in Fig. 3.

Supposing, now, that all of the disks and the wheel I are set to expose 0 through their respective reading-openings, the operation of the machine is as follows: Suppose the first sale made is thirty cents. The clerk receiving the money would first press down the key A', thereby sounding the gong and releasing the money-drawer. He would then turn the hand K to the number 30 on the dial B, as shown by the dotted lines in Fig. 1. After making change, if necessary, and depositing the money in the drawer, he would close the drawer, which would automatically become locked. The hand K would remain at 30, and the number 30 would appear through the reading-opening upon the wheel I. Upon making the next sale he would first depress the key A' to release the drawer and sound the gong, and by that act would retract the locking-dogs S and T from engagement with their ratchets, whereupon the spring J would at once reset the hand K to 0.

It will be readily understood from the description of the parts that the retraction of the hand K would not retract the registering-wheel I, for the latter would be held by its dog Y, and the dog d would merely slip back with its ratchet H. If this second sale should have been of the amount of seventy cents, the wheel I would then have made one complete revolution and 0 would appear through its reading-opening, while its pin j would have engaged with a tooth of the pinion i and turned the disk P' one notch to expose the number 1 through its reading-opening, and thus indicating a total registry of one dollar, and so on. The same operation is true of the hand L, upon

turning which to the left, for instance, until it points to "\$4," the pinion G, by its engagement with the pinion p, will turn the latter four notches to cause the number 4 on the disk Q' to be exposed through its reading-opening. The hand L would continue to point to "\$4" until the key A' was again depressed preparatory to another operation of the machine, whereupon said hand and the double ratchet a b would spring back to their normal position of rest. The teeth of the ratchet b, however, would merely slip under the dog c, and the pinion G would remain in its new position, being held by the spring locking-dog B', so that upon again moving the hand L, for instance, to "\$5," the pinion G would be turned still farther, until, by its continued engagement with the pinion p, the number 9 on the disk Q' would be exposed through its reading-opening, and so on.

Where dollars and cents are required to be registered and indicated at one operation of the machine, both hands may be operated, either simultaneously or successively, and their simultaneous resetting would occur upon depressing the key A'.

It will be seen that the numbers exposed through the upper row of reading-openings will indicate only dollars, of which those on the disk Q' would represent units, those on the disk Q" tens, and those on the disk Q''' hundreds. The lower row would represent both dollars and cents, the cents being represented on the wheel I, the units of dollars on the disk P', the tens of dollars on the disk P'', and the hundreds of dollars on the disk P'''.

It will also be seen that the total amount registered on each set of disks at any time may be seen at a glance by mere numerical reading without the necessity of any addition. Thus in the lower set, if the number 30 on the wheel I be exposed through its reading-opening, the number 1 on the disk P', the number 2 on the disk P'', and the number 3 on the disk P''', a total registry of "\$321.30" would be clearly indicated. In the same manner in the upper set, if the number 9 on the disk Q' were exposed, the number 2 on the disk Q", and the number 1 on the disk Q''', a total registry of "\$129" would be indicated on this set of disks.

The back of the case is provided with any suitable locked door, by opening which access may be had to buttons f' upon the rear end of each of the shafts N' N'' N''' and O' O'' O''', by means of which the disks are readily reset to zero after the readings have been taken at the end of a day's business.

It will be understood that the only office of the ratchet a b and spring-dog c is to furnish a ratchet-and-pawl connection between the shaft E and pinion G and to serve by the engagement of the ratchet a with the locking-dog S as a means of locking the shaft E with its hand L in any position to which the hand may be turned. Such being the case, it is evident that the ratchet-and-pawl connection, instead of consisting of the ratchet b and dog c, might be

interposed directly between the shaft E and the hub of the pinion G, in the usual manner of such connections, so that the pinion G would be actuated directly by the shaft E, in which event the only office of the ratchet a b would be to serve as a locking device for the hand L, for which purpose it might be merely a single ratchet, or any other suitable locking device might be employed in its stead. The same is true of the ratchet H and the wheel I upon the sleeve F.

Again, the numbers on the wheel I might be omitted and said wheel, instead of being a combined ratchet and registering wheel, be simply a pinion-wheel similar to the pinion G, in which event it would be arranged to engage constantly with the pinion i in the same manner that the pinion G meshes with the pinion p. In such case the pinion i would preferably be made larger and be provided with twenty teeth, to correspond with the teeth of the wheel I. The numbers on the disk P' (also made larger) would be changed to multiples of five from 0 to 95, inclusive, and would indicate cents. The pinion m would, through the medium of the pinion k and its pin l, be turned one notch for each complete revolution of the pinion i, as under the present construction, but the numbers on the disk P'' would indicate units of dollars and those on the disk P''' tens of dollars, while a fourth might be provided to indicate hundreds of dollars, all as will be readily understood.

Again, the construction of the machine might be simplified by dispensing with the upper set of registering mechanism and arranging the pinion G to actuate the same dollar-wheel which is actuated by the cent-wheel of the lower set. In this manner the operations of both the hands K and L would be registered on the same set of registering mechanism, the former through the medium of the wheel I and the latter through the medium of the pinion G.

Again, while we have shown and described the retracting-spring for the shaft E and sleeve F as consisting of a single coiled spring, J, it will be understood that separate springs may be employed for said shaft and sleeve, if desired.

Having thus fully described our invention, we claim—

1. In a cash register and indicator, the combination of a numbered dial, a central shaft, an operating index-hand secured to said shaft in front of said dial, a zero-stop for said hand, a retracting-spring for said shaft, a ratchet secured upon said shaft and a wheel loose upon said shaft, an actuating dog between said ratchet and wheel, registering mechanism actuated by said wheel, a locking-dog engaging with said ratchet, a releasing-key, a locking-bolt actuated by said releasing-key, a drawer locked by said bolt, a gong, its hammer and tripping-arm, and a link connecting said releasing-key with the locking-dog and tripping-arm, substantially as described.

2. In a cash register and indicator, the com-

bination of a numbered dial, a central shaft, a sleeve upon the shaft, a pinion on the shaft and ratchet-and-pawl connection between said pinion and shaft, a wheel upon said sleeve and 5 ratchet-and-pawl connection between said sleeve and wheel, a retracting-spring for said shaft and sleeve, two operating index-hands in front of said dial, one for indicating dollars and one for indicating cents, and secured one 10 to said shaft and one to said sleeve, a zero-stop for said hands, locking mechanism applied to said shaft and sleeve, and registering mechanism actuated by the pinion upon the shaft and the wheel upon the sleeve, substantially as de- 15 scribed.

3. In a cash register and indicator, the combination of a numbered dial, a central shaft, a sleeve upon the shaft, a pinion on the shaft and ratchet-and-pawl connection between said 20 pinion and shaft, a wheel upon said sleeve and ratchet-and-pawl connection between said sleeve and wheel, a retracting-spring for said shaft and sleeve, two operating index-hands in front of said dial, one for indicating dollars 25 and one for indicating cents, and secured one to said shaft and one to said sleeve, a zero-stop for said hands, locking mechanism applied to said shaft and sleeve, registering mechanism actuated by the pinion upon the shaft and the 30 wheel upon the sleeve, a releasing-key, and connecting mechanism between said releasing key and locking mechanism, substantially as described.

4. In a cash register and indicator, the combination of a numbered dial, a central shaft, a sleeve upon the shaft, a pinion on the shaft and ratchet-and-pawl connection between said pinion and shaft, a wheel upon said sleeve and ratchet-and-pawl connection between said 40 sleeve and wheel, a retracting-spring for said shaft and sleeve, two operating index-hands in front of said dial, one for indicating dollars and one for indicating cents, and secured one to said shaft and one to said sleeve, a zero-stop for said hands, locking mechanism applied to said shaft and sleeve, registering mechanism actuated by the pinion upon the shaft and the wheel upon the sleeve, a releasing-key, a gong 45 and gong-hammer, and connecting mechanism between said releasing-key and the gong-hammer and locking mechanism, substantially as described.

5. In a cash register and indicator, the combination of a numbered dial, a central shaft, a 55 sleeve upon the shaft, a pinion on the shaft and ratchet-and-pawl connection between said pinion and shaft, a wheel upon said sleeve and ratchet-and-pawl connection between said sleeve and wheel, a retracting-spring for said 60 shaft and sleeve, two operating index-hands in front of said dial, one for indicating dollars and one for indicating cents, and secured one to said shaft and one to said sleeve, a zero-stop for said hands, locking mechanism applied to said 65 shaft and sleeve, registering mechanism actuated by the pinion upon the shaft and the wheel upon the sleeve, a releasing-key, a lock-

ing-bolt actuated by said releasing-key, a drawer locked by said bolt, and connecting mechanism between said releasing-key and locking mechanism, substantially as described. 70

6. In a cash register and indicator, the combination of a numbered dial, a central shaft, a sleeve upon the shaft, a pinion on the shaft and ratchet-and-pawl connection between 75 said pinion and shaft, a wheel upon said sleeve and ratchet-and-pawl connection between said shaft and sleeve, a retracting-spring for said shaft and sleeve, two operating index-hands in front of said dial, one for indicating dollars 80 and one for indicating cents, and secured one to said shaft and one to said sleeve, a zero-stop for said hands, locking mechanism applied to said shaft and sleeve, registering mechanism actuated by the pinion upon the shaft 85 and the wheel upon the sleeve, a releasing-key, a locking-bolt actuated by said releasing-key, a drawer locked by said bolt, a gong and gong-hammer, and connecting mechanism between said releasing-key and the gong-hammer and locking mechanism, substantially as described. 90

7. In a cash register and indicator, the combination of a numbered dial, a central shaft, a sleeve upon said shaft, a ratchet secured to said shaft and a pinion loose upon said shaft, an actuating-dog between said ratchet and pinion, a ratchet secured to said sleeve and a wheel loose upon said sleeve, an actuating-dog between said ratchet and wheel, a retracting-spring for said sleeve and shaft, two operating 100 index-hands in front of said dial, one for indicating dollars and one for indicating cents, and secured one to said shaft and one to said sleeve, a zero-stop for said hands, a locking-dog for each of said ratchets, and registering 105 mechanism actuated by the pinion upon the shaft and the wheel upon the sleeve, substantially as described. 110

8. In a cash register and indicator, the combination of a numbered dial, a central shaft, a sleeve upon said shaft, a ratchet secured to said shaft and a pinion loose upon said shaft, an actuating-dog between said ratchet and pinion, a ratchet secured to said sleeve and a wheel loose upon said sleeve, an actuating-dog between 115 said ratchet and wheel, a retracting-spring for said sleeve and shaft, two operating index-hands in front of said dial, one for indicating dollars and one for indicating cents, and secured one to said shaft and one to said sleeve, a zero-stop for said hands, a locking-dog for each of said ratchets, registering mechanism actuated by the pinion upon the shaft and the wheel upon the sleeve, a releasing-key, and connecting mechanism between said 120 releasing-key and locking-dogs, substantially as described. 125

9. In a cash register and indicator, the combination of a numbered dial, a central shaft, a sleeve upon said shaft, a ratchet secured to 130 said shaft and a pinion loose upon said shaft, an actuating-dog between said ratchet and pinion, a ratchet secured to said sleeve and a wheel loose upon said sleeve, an actuating-dog

between said ratchet and wheel, a retracting-spring for said sleeve and shaft, two operating index-hands in front of said dial, one for indicating dollars and one for indicating cents, and 5 secured one to said shaft and one to said sleeve, a zero-stop for said hands, a locking-dog for each of said ratchets, registering mechanism actuated by the pinion upon the shaft and the wheel upon the sleeve, a releasing-key, a gong 10 and gong-hammer, and connecting mechanism between said releasing-key and the locking-dogs and gong-hammer, substantially as described.

10. In a cash register and indicator, the combination of a numbered dial, a central shaft, a 15 sleeve upon said shaft, a ratchet secured to said shaft and a pinion loose upon said shaft, an actuating-dog between said ratchet and pinion, a ratchet secured to said sleeve and a 20 wheel loose upon said sleeve, an actuating-dog between said ratchet and wheel, a retracting-spring for said sleeve and shaft, two operating index-hands in front of said dial, one for indicating dollars and one for indicating cents, and 25 secured one to said shaft and one to said sleeve, a zero-stop for said hands, a locking-dog for each of said ratchets, registering mechanism actuated by the pinion upon the shaft and the wheel upon the sleeve, a releasing-key, a locking-bolt 30 actuated by said releasing-key, a drawer locked by said bolt, and connecting mechanism between said releasing-key and locking-dogs, substantially as described.

11. In a cash register and indicator, the combination of a numbered dial, a central shaft, a 35 sleeve upon said shaft, a ratchet secured to said shaft and a pinion loose upon said shaft, an actuating-dog between said ratchet and pinion, a ratchet secured to said sleeve and a 40 wheel loose upon said sleeve, an actuating-dog between said ratchet and wheel, a retracting-spring for said sleeve and shaft, two operating index-hands in front of said dial, one for indicating dollars and one for indicating cents, and 45 secured one to said shaft and one to said sleeve, a zero-stop for said hands, a locking-dog for each of said ratchets, registering mechanism actuated by the pinion upon the shaft and the wheel upon the sleeve, a releasing-key, a locking-bolt 50 actuated by said releasing-key, a drawer locked by said bolt, a gong and gong-hammer, and connecting mechanism between said releasing-key and the locking-dogs and gong-hammer, substantially as described.

12. In a cash register and indicator, the combination of a dial provided with two series of numbers indicating, respectively, dollars and cents, a central shaft at right angles to said dial, a sleeve journaled upon said shaft, a 55 ratchet secured to said shaft and a pinion loose upon said shaft, an actuating-dog between said ratchet and pinion, a ratchet secured to said sleeve and a wheel loose upon said sleeve, an actuating-dog between said ratchet and wheel, a 60 retracting-spring for said sleeve and shaft, two operating index-hands in front of said dial, one for indicating dollars and one for indicating cents, and one to said sleeve, a zero-stop for said hands,

ing cents, and secured one to said shaft and one to said sleeve, a zero-stop for said hands, a locking-dog for each of said ratchets, and two 70 sets of registering mechanism, one set arranged to be actuated by the pinion upon the shaft and the other by the wheel upon the sleeve, substantially as and for the purpose described.

13. In a cash register and indicator, the combination of a dial provided with two series of numbers indicating, respectively, dollars and cents, a central shaft at right angles to said dial, a sleeve journaled upon said shaft, a ratchet secured to said shaft and a pinion loose 80 upon said shaft, an actuating-dog between said ratchet and pinion, a ratchet secured to said sleeve and a wheel loose upon said sleeve, an actuating-dog between said ratchet and wheel, a retracting-spring for said sleeve and shaft, 85 two operating index-hands in front of said dial, one for indicating dollars and one for indicating cents, and secured one to said shaft and one to said sleeve, a zero-stop for said hands, a locking-dog for each of said ratchets, two 90 sets of registering mechanism, one set arranged to be actuated by the pinion upon the shaft and the other by the wheel upon the sleeve, a releasing-key, and connecting mechanism between said releasing-key and locking-dogs, substantially as described.

14. In a cash register and indicator, the combination of a dial provided with two series of numbers indicating, respectively, dollars and cents, a central shaft at right angles to said dial, a sleeve journaled upon said shaft, a ratchet secured to said shaft and a pinion loose upon said shaft, an actuating-dog between said ratchet and pinion, a ratchet secured to said sleeve and a wheel loose upon said sleeve, an actuating-dog between said ratchet and wheel, a retracting-spring for said sleeve and shaft, 100 two operating index-hands in front of said dial, one for indicating dollars and one for indicating cents, and secured one to said shaft and one to said sleeve, a zero-stop for said hands, a locking-dog for each of said ratchets, two sets of registering mechanism, one set arranged to be actuated by the pinion upon the shaft and the other by the wheel upon the sleeve, a releasing-key, a gong, its hammer and tripping-arm, and a link connecting said releasing-key with the locking-dogs and tripping-arm, substantially as described.

15. In a cash register and indicator, the combination of a dial provided with two series of numbers indicating, respectively, dollars and cents, a central shaft at right angles to said dial, a sleeve journaled upon said shaft, a ratchet secured to said shaft and a pinion loose 110 upon said shaft, an actuating-dog between said ratchet and pinion, a ratchet secured to said sleeve and a wheel loose upon said sleeve, an actuating-dog between said ratchet and wheel, a retracting-spring for said shaft and sleeve, 115 two operating index-hands in front of said dial, one for indicating dollars and one for indicating cents, and secured one to said shaft and one to said sleeve, a zero-stop for said hands,

a locking-dog for each of said ratchets, two sets of registering mechanism, one set arranged to be actuated by the pinion upon the shaft and the other by the wheel upon the sleeve, a releasing-key, a locking-bolt actuated by said releasing-key, a drawer locked by said bolt, and a link connecting said releasing-key and locking-dogs, substantially as described.

16. In a cash register and indicator, the combination of a dial provided with two series of numbers indicating, respectively, dollars and cents, a central shaft at right angles to said dial, a sleeve journaled upon said shaft, a ratchet secured to said shaft and a pinion loose upon said shaft, an actuating-dog between said ratchet and pinion, a ratchet secured to said sleeve and a wheel loose upon said sleeve, an actuating-dog between said ratchet and wheel, a retracting-spring for said shaft and sleeve, two operating index-hands in front of said dial, one for indicating dollars and one for indicating cents, and secured one to said shaft and one to said sleeve, a zero-stop for said hands, a locking-dog for each of said ratchets, two sets of registering mechanism, one set arranged to be actuated by the pinion on the shaft and the other by the wheel upon the sleeve, a releasing-key, a locking-bolt actuated by said releasing-key, a drawer locked by said bolt, a gong, its hammer and tripping-arm, and a link connecting said releasing-key with the locking-dogs and tripping-arm, substantially as described.

17. In a cash register and indicator, the combination of a dial provided with two series of numbers indicating, respectively, dollars and cents, a central shaft at right angles to said dial, a sleeve journaled upon said shaft, a ratchet secured to said shaft and a pinion loose upon said shaft, an actuating-dog between said ratchet and pinion, a ratchet secured to said sleeve and a combined ratchet and registering wheel loose upon said sleeve, an actuating-dog between said ratchet and the combined ratchet and registering wheel, a retracting-spring for said sleeve and shaft, two operating index-hands in front of said dial, one for indicating dollars and one for indicating cents, and secured one to said shaft and one to said sleeve, a zero-stop for said hands, a locking-dog for each of said ratchets, and two sets of registering mechanism, one set arranged to be actuated by the pinion upon the shaft and the other by the registering-wheel upon the sleeve, substantially as described.

18. In a cash register and indicator, the combination of a dial provided with two series of numbers indicating, respectively, dollars and cents, a central shaft at right angles to said dial, a sleeve journaled upon said shaft, a ratchet secured to said shaft and a pinion loose upon said shaft, an actuating-dog between said ratchet and pinion, a ratchet secured to said sleeve and a combined ratchet and registering wheel loose upon said sleeve, an actuating-dog between said ratchet and the combined ratchet and registering wheel, a retracting-spring for

said sleeve and shaft, two operating index-hands in front of said dial, one for indicating dollars and one for indicating cents, and secured one to said shaft and one to said sleeve, a zero-stop for said hands, a locking-dog for each of said ratchets, two sets of registering mechanism, one set arranged to be actuated by the pinion upon the shaft and the other by the registering-wheel upon the sleeve, a releasing-key, a gong, its hammer and tripping-arm, and a link connecting said releasing-key with the locking-dogs and tripping-arm, substantially as described.

19. In a cash register and indicator, the combination of a dial provided with two series of numbers indicating, respectively, dollars and cents, a central shaft at right angles to said dial, a sleeve journaled upon said shaft, a ratchet secured to said shaft and a pinion loose upon said shaft, an actuating-dog between said ratchet and pinion, a ratchet secured to said sleeve and a combined ratchet and registering wheel loose upon said sleeve, an actuating-dog between said ratchet and the combined ratchet and registering wheel, a retracting-spring for said shaft and sleeve, two operating index-hands in front of said dial, one for indicating dollars and one for indicating cents, and secured one to said shaft and one to said sleeve, a zero-stop for said hands, a locking-dog for each of said ratchets, two sets of registering mechanism, one set arranged to be actuated by the pinion upon the shaft and the other by the registering-wheel upon the sleeve, a releasing-key, a locking-bolt actuated by said releasing-key, a drawer locked by said bolt, and a link connecting said releasing-key with the locking-dogs, substantially as described.

20. In a cash register and indicator, the combination of a dial provided with two series of numbers indicating, respectively, dollars and cents, a central shaft at right angles to said dial, a sleeve journaled upon said shaft, a ratchet secured to said shaft and a pinion loose upon said shaft, an actuating-dog between said ratchet and pinion, a ratchet secured to said sleeve and a combined ratchet and registering wheel loose upon said sleeve, an actuating-dog between said ratchet and the combined ratchet and registering wheel, a retracting-spring for said shaft and sleeve, two operating index-hands in front of said dial, one for indicating dollars and one for indicating cents, and secured one to said shaft and one to said sleeve, a zero-stop for said hands, a locking-dog for each of said ratchets, two sets of registering mechanism, one set arranged to be actuated by the pinion on the shaft and the other by the registering-wheel upon the sleeve, a releasing-key, a locking-bolt actuated by said releasing-key, a drawer locked by said bolt, a gong, its hammer and tripping-arm, and a link connecting said releasing-key with the locking-dogs and tripping-arm, substantially as described.

21. In a cash register and indicator, the combination of a numbered dial, a central shaft, a sleeve journaled on said shaft, two operating

index-hands in front of said dial, secured one to said shaft and one to said sleeve, a zero-stop for said hands, locking mechanism applied to said shaft and sleeve, registering mechanism actuated by the operation of said hands, and a coiled spring connecting said shaft and sleeve, whereby upon turning one of said hands said spring is wound up from the outside and upon turning the other of said hands it is wound up from the inside, substantially as described.

22. In a cash register and indicator, the combination of a numbered dial, a central shaft, a sleeve journaled upon said shaft, a ratchet secured to said shaft, a coiled spring connected at one end to said ratchet and at the other end to said sleeve, two operating index hands in front of said dial, secured one to said shaft and one to said sleeve, a zero-stop for said hands, locking mechanism applied to said shaft and sleeve, and registering mechanism actuated by the operation of said hands, whereby upon turning one of said hands said spring is wound up from the outside and upon turning the other of said hands it is wound up from the inside, substantially as described.

23. In a cash register and indicator, the combination of a numbered dial, a central shaft, a sleeve journaled upon said shaft, a pinion upon said shaft and ratchet-and-pawl connection between said shaft and pinion, a wheel upon said sleeve and ratchet-and-pawl connection between said sleeve and wheel, a coiled spring connecting said shaft and sleeve, two operating index-hands in front of said dial, secured one to said shaft and one to said sleeve, a zero-stop for said hands, locking mechanism applied to said shaft and sleeve, and registering mechanism actuated by the operation of said hands, substantially as described.

24. In a cash register and indicator, the combination of a numbered dial, a central shaft, a sleeve journaled upon said shaft, a ratchet secured to said shaft and a pinion loose upon said shaft, an actuating-dog between said ratchet and pinion, a ratchet secured to said sleeve and a wheel loose upon said sleeve, an actuating-dog between said ratchet and wheel, a coiled spring connected at one end to said sleeve and at the other end to the ratchet upon the shaft, two operating index-hands in front of said dial, secured one to said shaft and one to said sleeve, a zero-stop for said hands, a locking-dog for each of said ratchets, and registering mechanism actuated by the pinion on the shaft and the wheel upon the sleeve, substantially as described.

25. In a cash register and indicator, the combination of a dial provided with two rows of numbers indicating, respectively, dollars and cents, a central shaft at right angles to said dial, a sleeve journaled upon said shaft, a ratchet secured to said shaft and a pinion loose upon said shaft, an actuating-dog between said ratchet and pinion, a ratchet secured to said sleeve and a combined ratchet and registering wheel loose upon said sleeve,

an actuating-dog between said ratchet and the combined ratchet and registering wheel, a coiled spring connected at one end to said sleeve and at the other end to the ratchet secured upon the shaft, a zero-stop for the ratchet upon the shaft, two operating index-hands in front of said dial, one for indicating dollars and one for indicating cents, and secured one to said shaft and one to said sleeve, a zero-stop for the hand upon the sleeve, a locking-dog for each of said ratchets, two sets of registering mechanism, one set arranged to be actuated by the pinion upon the shaft and the other by the registering-wheel upon the sleeve, a releasing-key, a locking-bolt secured to said releasing-key, a drawer locked by said bolt, a gong, its hammer and tripping-arm, and a link connecting said releasing-key with the locking-dogs and tripping-arm, substantially as described.

26. The combination and arrangement of the numbered dial B, the shaft E, provided with the hand L, ratchet a b, pinion G, loose upon the shaft E and connected to the ratchet b by a dog, c, the sleeve F, journaled upon the shaft E and connected to the ratchet a by a coiled spring, J, the ratchet H, secured to said sleeve, and the wheel I, loose upon said sleeve, the ratchet H and wheel I being connected by a dog, d, a hand, K, secured to the sleeve F, stops f and g for the hand K and ratchet a, registering mechanism actuated by the pinion G from the hand L and the wheel I from the hand K, and locking-dogs S and T for the ratchets a and H, substantially as described.

27. The combination and arrangement of the numbered dial B, the shaft E, provided with the hand L, ratchet a b, pinion G, loose upon the shaft E and connected to the ratchet b by a dog, c, the sleeve F, journaled upon the shaft E and connected to the ratchet a by a coiled spring, J, the ratchet H, secured to said sleeve, and the wheel I, loose upon said sleeve, the ratchet H and wheel I being connected by a dog, d, a hand, K, secured to the sleeve F, stops f and g for the hand K and ratchet a, registering mechanism actuated by the pinion G from the hand L and the wheel I from the hand K, locking-dogs S and T for the ratchets a and H, releasing-key A', and link F', connecting said releasing-key with the locking-dogs, substantially as described.

28. The combination and arrangement of the numbered dial B, the shaft E, provided with the hand L, ratchet a b, pinion G, loose upon the shaft E and connected to the ratchet b by a dog, c, the sleeve F, journaled upon the shaft E and connected to the ratchet a by a coiled spring, J, the ratchet H, secured to said sleeve, and the wheel I, loose upon said sleeve, the ratchet H and wheel I being connected by a dog, d, a hand, K, secured to the sleeve F, stops f and g for the hand K and ratchet a, registering mechanism actuated by the pinion G from the hand L and the wheel I from the hand K, locking-dogs S and T for the ratchets a and H, releasing-key A', locking-bolt C', secured to the key A', drawer C, locked by the

bolt C', and link F', connecting the key A' with the locking-dogs S and T, substantially as described.

29. The combination and arrangement of the numbered dial B, the shaft E, provided with a hand, L, double ratchet a b, pinion G, loose upon the shaft E and connected to the ratchet b by a dog, c, the sleeve F, journaled upon the shaft E and connected to the ratchet a by a coiled spring, J, the ratchet H, secured to said sleeve, and the combined ratchet and registering wheel I, loose upon said sleeve, said ratchet H and wheel I being connected by a dog, d, a hand, K, secured to the sleeve F, a stop, g, for the ratchet a, and a stop, f, upon the dial for the hand K, two sets of registering mechanism, the one actuated by the pinion G from the hand L and the other by the wheel I from the hand K, the locking-dogs S T, trip lever U, bell-crank V, gong-hammer W, gong X, connecting-link F', united at one end to the dogs S T and lever U by means of the cross-bar e' and at the other end to the releasing-key A', the key A', locking-bolt C', and drawer C, substantially as and for the purpose described.

30. The combination and arrangement of the dial B, provided with the upper row of reading-openings, v, the shaft E, index-hand L, ratchet b, secured to said shaft, pinion G, loose upon said shaft, pinions p q r, the former meshing with the pinion G, lugs s t upon the pinions p q, and registering-disks Q', Q'', and Q''', connected to the pinions p q r, respectively, and each provided with a series of numbers exposed one at a time through its corresponding reading-opening v, whereby the amount registered on said disks at any time is numerically indicated by the numbers exposed

through said reading-openings without the necessity of addition, substantially as described. 40

31. The combination and arrangement of the dial B, provided with two sets of reading-openings, v, the shaft E, provided with a hand, L, double ratchet a b, secured to said shaft, pinion G, loose upon said shaft and connected to the ratchet b by a dog, c, the sleeve F, journaled upon the shaft E and connected to the ratchet a by a coiled spring, J, the ratchet H, secured to said sleeve, and the combined ratchet and registering wheel I, loose upon said sleeve, said ratchet and wheel being connected by a dog, d, a hand, K, secured to the sleeve F, the pinions p q r, actuated by the pinion G, the disks Q', Q'', and Q''', connected to the pinions p q r, respectively, and each provided with a series of numbers exposed one at a time through its reading-opening v, the pinions N', N'', and N''', actuated by the wheel I, and the disks k m o, connected to the pinions N', N'', and N''', respectively, and each provided with a series of numbers exposed one at a time through its reading-opening v, whereby the respective total amounts registered at any time upon the two sets of disks Q' Q'' Q''' 65 and P' P'' P''' and wheel I are each numerically indicated by the numbers exposed through the reading-openings v without the necessity of addition, substantially as described. 55
